UNITED STATES PATENT OFFICE.

ALBERT S. JANIN, OF NEW YORK, N. Y., ASSIGNOR OF ONE-THIRD TO AMELIA JANIN, OF BROOKLYN, NEW YORK.

TROLLEY.

No. 895,864.

Specification of Letters Patent.

Patented Aug. 11, 1908.

Application filed December 12, 1906. Serial No. 347,409.

To all whom it may concern:

Be it known that I, ALBERT S. JANIN, a citizen of the United States, and a resident of the city of New York, Rosebank, borough of Richmond, in the county of Richmond and State of New York, have invented a new and Improved Trolley, of which the following is a full, clear, and exact description.

The purpose of the invention is to provide a trolley of very simple, durable and economic construction, wherein the frame is of such shape that in itself it acts as a guide for the wire to and from the contact roller, and as a fender for the gearing and joints of the frame.

Another purpose of the invention is to provide housed gearing for the members of the frame, whereby in all positions of the frame the gearing is absolutely protected from entanglement with the trolley wire, and in fact from any dangerous contact therewith.

A further purpose of the invention is to render the contact roller noiseless in action and to provide the contact roller with an accompanying adjustable scraper and means for holding the roller stationary when desired, and the scraper in any position to which it may have been adjusted.

Another purpose of the invention is to provide a means whereby with perfect safety to the operator the trolley may be adjusted from the inside of the car to any position intermediate of the roof and the trolley wire and be held securely in adjusted position.

The invention consists in the novel construction and combination of the several parts, as will be hereinafter fully set forth and pointed out in the claims.

Reference is to be had to the accompanying drawings forming a part of this specification, in which similar characters of reference indicate corresponding parts in all the figures.

Figure 1 is a side elevation of the improved trolley; Fig. 2 is a front elevation thereof and a section through the adjusting mechanism; Fig. 3 is an enlarged side elevation of an end portion of the contact roller and adjacent portion of the frame; Fig. 4 is an end view of the parts shown in Fig. 3; Fig. 5 is a sectional side elevation of the upper portion of a car and a side elevation of the applied trolley, the latter appearing in elevated position; Fig. 6 is a sectional front elevation of

the contact roller; Fig. 7 is an end view of the contact roller; Fig. 8 is an outer face view of a bearing plate for a contact roller; Fig. 9 is a sectional side elevation of the upper portion of a car and a side elevation of the applied trolley, the latter being illustrated as held closed to the roof of the car; Fig. 10 is a plan view of the improved trolley and the portion of the roof of the car to which it is attached; Fig. 11 is an edge view of one of the end guard plates for the contact roller; and Fig. 12 is a view of the outer face of the said guard plate, and also shows in dotted lines an adjustable position of the plate carrying the scraper.

The trolley frame A is of that type known as a pivoted diamond frame, and consists of four upper members 10, two at each side, and four lower members 11, which are likewise arranged two at each side. The upper members 10 are pivoted to a support to be herein-after described, and the lower members 11 are pivoted to a base B adapted for attachment to the roof of the car C. The upper and the lower members 10 and 11 of the said frame are pivotally connected by means of rods 12, and the upper members 10 at each side of the center of the frame are braced by stay rods 13 and the corresponding lower members 11 of the frame are connected by stay rods 14 as is best shown in Fig. 2.

Springs 15 are attached to the end pivot rods 12 and to the lower stay rods 14, the springs from one end portion of the frame crossing those extending from the opposing end portion as is illustrated in Fig. 1. The lower ends of the lower members 11 of the frame are enlarged and are curved inwardly to a pivotal connection with uprights 16 from the ends of the base B, so that in the event a wire should possibly slip along the frame and should momentarily engage with the inner terminals 17 of the said lower members 11 of the frame, the wire by reason of the shape of the said lower terminals 17 would be made to slip travel up the frame, and would in no manner interfere with segmental gears 18, which are made integral with the inner faces of the said lower terminals 17 of said lower members of the frame, the said gears 18 being made to mesh as is clearly shown in Fig. 1.

The frame A differs materially from frames of like type in that where the upper members 10 are pivotally connected with the lower

members 11, the frame is rounded off, as is particularly shown at 19 in Fig. 1, so that no sharp or abrupt surfaces are presented to the wires that may engage with the frame, and therefore the frame in its entirety is a guide for the wire. If the wire should engage with the upper members of the frame, the wire will be directed to the contact roller D to be hereinafter particularly described; and should the wire engage with the lower member of the frame it will still be directed to the top and is absolutely prevented from interfering with the gear connections 18 between the lower members of the frame, as well as the gear connection of the frame, which action of the wire always sliding upward being due to the ovate form of the frame and the fact that there are no stops to be encountered.

The upper ends of the upper members 10 of the frame A are upwardly and inwardly curved and are enlarged, and are inwardly as well as upwardly curved to a greater or lesser extent as is shown at 20 particularly in Figs. 3 and 4. Segmental gears 21 are made integral with or are attached to the upper enlarged ends of the upper frame members 10, and the upper ends of said upper frame members are pivotally attached by means of pivot bolts 22 or their equivalents to cheek pieces 24, which cheek pieces 24 are provided with suitable openings 23 for the reception of the said pivot bolts 22 as is illustrated in Fig. 12. Each cheek piece 24 is provided with a downwardly-curved, outwardly-extending lip 25 at its upper end, and the meshing gears 21 of the said upper members 10 lie beneath and at each side of the lips 25, which act to carry a wire over the gears 21, so as to prevent the possibility of the wire interfering with said gears. In fact, the lips 25 act as housings for the gears 21 but the upper enlargements 20 are so shaped that in all positions of the frame they act as guards for the gears and keep the wire in proper alinement.

Each cheek piece 24 is preferably of oval shape, as illustrated in Fig. 12, and is provided with a central opening 26, and an opening 27 adjacent to one side at its lower end. A bearing plate 28 is located adjacent to the inner face of each cheek piece 24. These bearing plates 28, one of which is shown in Fig. 8, are of corresponding shape to the shape of the cheek pieces 24, and are preferably provided at the top and bottom 55 of their outer faces with flanges 29 that engage the inner faces of the cheek pieces 24 as is best shown in Fig. 3. Each bearing plate 28 is provided with a central opening 30, through which a pivot bolt 31 extends from its corresponding cheek piece 24, the head of which bolt is designated as 39^a. Each bearing plate 28 is also provided with two apertures 32 and 32^a, located adjacent to the flanges 29, but the said openings 32 and 32^a are diagonally opposite, as is also

shown in Fig. 8, said openings being adapted to receive a set screw 33, which is passed through the lower openings 27 in the cheek pieces or plates 24, so as to hold the bearing plates 28 in adjusted position, since in operation they are intended to be reversed at different times for a purpose to be hereinafter described.

Each bearing plate 28 is also provided at the central portion of one end adjacent to the flange 29 at said end, with apertures 34 located one above the other as is shown in Fig. 8, and with a transverse slot 35 that extends through from an outer edge to about the center of the plate above the central opening 30. These slots 35 in the bearing plates 28 are adapted to receive the flattened outer end portions 36 of the shaft 37 for the contact roller D heretofore mentioned, so as to prevent said shaft 37 from turning; and said shaft 37 is also provided at each end with a threaded section 38, adapted to receive nuts 39 whereby to hold said shaft in position.

The contact roller D consists of a metal shell 40 in which shell a rubber cushion 41 is fitted, engaging with its inner face, said cushion being preferably of tubular form and held to place by a coiled spring 42, bands or the equivalent thereof, said cushion 41 being intended to deaden the sound when the roller is engaged with any object. At each end of the shell or body 40 of the roller, an annular flange 43 is formed, and said flanges extend around disks 44 that are secured upon the end portions of the shaft 37, and the opposing faces of the disks 44 and flanges 43 are grooved to receive balls 45, so that the contact roller D turns upon ball or roller bearings. These balls or rollers 45 are introduced into their races through openings made in the disks 44, which openings are closed by plugs 46 having recesses in their peripheral surfaces. These plugs 46 are held in place by means of screws 47, since the recesses that receive the said plugs do not extend through the disks, as is clearly shown in Fig. 6.

A scraper 48 is employed in connection with the contact roller D, being normally 115 below the said roller; and said scraper has end flanges 49 that are secured to the inner faces of the bearing plates 28 by means of screws 50 or their equivalents, passed through said flanges into the aforesaid 120 openings or apertures 34 in the bearing plates as is clearly shown in Fig. 3.

The contact roller D can be held stationary when desired so as to act in the capacity of a scraper, by introducing set screws 51, or the equivalents thereof, into one or both ends of the roller, which set screws are carried by the bearing plates 28 and pass through openings 28^a in the plates and openings 28^b in the heads of the roller D; and it is evident that by 130

loosening the screw 33 the bearing plates 28 can be turned on their pivots 31, so as to have the roller D above the scraper 48, which is the normal position of said parts, or that the 5 scraper may be brought to a position above the roller. Thus scraper 48 acts independent of the roller D, but in all said conditions of use the pivots 31 are prevented from turning, due to the shape of their countersunk 10 heads.

I desire it to be understood that the trolley may be drawn down in the customary manner, but preferably the trolley is operated by the mechanism shown in Figs. 2, 5, 9 and 10, 15 which mechanism is operated from a point within the car. Said mechanism consists of substantially U-shaped bearings 52 located longitudinally of the roof of the car, one at each side of the base B as is particularly 20 shown in Figs. 5 and 10; and the upright member at the outer end of each bearing 52 is provided with a horizontal inward extension 53 at or near its upper end. Each bearing 52 contains a spirally grooved drum 54, 25 and these drums are mounted on a shaft 55, which shaft at its outer end is provided with a pinion 56, and the outer end portion of said shaft is divided and the divided parts are connected by a coupling 57 constructed of 30 insulating material.

The pinion 56 is made to mesh with a gear 58, and said gear 58 is secured to a shaft 59 that extends down through the clear story of the car as is shown in Figs. 5 and 9, and said 35 shaft at its lower end is provided with a hand wheel 60, or its equivalent, whereby said shaft may be readily turned. The shaft 59 is also provided adjacent to its lower end with a ratchet wheel 61, engaged by a pawl 62 40 mounted upon a suitable support in the car. Chains 63 are secured to the lower connecting or brace bars 14, preferably at the central portion of said bars, and said chains are likewise connected with the spiral drums 54 at 45 their outer end portions. Thus when the shaft 59 is turned in one direction, the chains 63 will wind in the spiral grooves of the drums 54, and if desired the frame may be made to closely fold up upon the roof of the car as 50 shown in Fig. 9 and be held in such position; or the said frame may be partially closed as desired. When the frame is entirely or partly closed, and it is desired to open the same to bring the contact roller D in engagement with the line wire 64, as shown in Fig. 5, the chains 63 upon turning the shaft 59 in a suitable direction will unwind; and when the frame is opened to its full extent the chains in commencing to wind in the opposite 55 direction on the drums will be engaged by the projecting members 53 of the brackets in which the drums are mounted, and will be checked, thus notifying the operator that the frame has been fully opened.

Having thus described my invention, I

claim as new, and desire to secure by Letters Patent,—

1. In a trolley, a collapsible diamond-shaped frame consisting of upper and lower pivotally connected members, said frame 70 having its surfaces rounded at the junction of its parts, and the upper ends of its upper members upwardly curved and inwardly inclined, whereby the frame is rendered a guide and director for the wire through its exterior 75 marginal surface.

2. In a trolley, a collapsible frame of a diamond-shaped type, consisting of upper and lower members, meshing gears at the opposing inner ends of the frame members, 80 which gears are at the inner face of said frame members whereby said members constitute protective elements for the gears, cheek pieces to which the inner ends of the upper members are pivoted, and combined 85 protective and guide lips extending over the upper set of gears.

3. In a trolley, a collapsible frame, the inner ends of the opposing members whereof are enlarged, gears located at the inner faces of 90 the enlarged ends of the frame partially concealed thereby, a base to which the lower frame ends are pivoted, cheek pieces to which the upper frame ends are pivoted, and lips at the upper outer portions of the said cheek 95 pieces that extend between and over the exposed portions of the upper gears.

4. In a trolley, a tension-controlled collapsible frame, a downwardly extending vertical shaft adapted to be carried within the 100 car, means for regulating the rotation of said shaft, a second shaft adapted to be mounted upon the car beneath the frame, bearings for the outer shaft arranged in pairs and located at the front and the rear of the frame, a gear 105 connection between the two shafts, a spiral drum secured to the outer shaft between the members of each of the bearings, devices for limiting the rotation of the said outer shaft in one or the other direction, said devices 110 operating over said drums, flexible connections between the drums and the frame, and means for insulating the outer from the inner or vertical shaft.

5. In a trolley, a car, a flexible frame 115 mounted upon the car, a line shaft, spirally grooved drums carried by the line shaft, one at each side of the frame and independent thereof, stops extending over said drums, flexible connections between the drums and the respective sides of the frame adapted to be wound upon or unwound from said drums and to engage with said stops, a drive shaft that extends down through the top of the car, a gear connection between the line and 120 the drive shafts, an insulating coupling for the line shaft located between the said gear connections and the drums, and a locking device for the drive shaft.

6. In a trolley, a contact roller, a cushion 125

located within the said roller in engagement with its inner peripheral surface, and springs for holding the cushion in place.

7. In a trolley, a frame provided with upper cheek pieces, bearing plates mounted to revolve on the cheek pieces, means for holding the bearing plates in adjusted position, which means are carried by the said cheek pieces, a contact roller mounted in the said bearing plates, and a scraper likewise carried by the bearing plates, being revolvably affixed thereto.

8. In a trolley, a collapsible frame of the diamond-shape type, the inner ends of the side members of the said frame being enlarged and inwardly curved, gears secured to the inner faces of the said inner end portions of the said side members, a base to which the inner ends of the lower frame members are pivoted, cheek pieces to which the inner ends of the upper members of the frame are pivoted, a contact roller located between the said cheek pieces, and guard lips extending from the upper portions of said cheek pieces over the upper gears protecting said gears.

9. In a trolley, a collapsible frame of the diamond-shape type, the inner ends of the side members of the said frame being enlarged and inwardly curved, gears secured to the inner faces of the said inner end portions of the said side members, a base to which the inner ends of the lower frame members are pivoted, cheek pieces to which the inner ends of the upper members of the frame are pivoted, guard lips that extend outwardly from the upper ends of the said cheek pieces over the upper gears protecting them, bearing plates mounted to turn in the said cheek pieces, means for locking the said bearing plates in adjusted position, means for holding the said contact roller stationary, and a scraper stationarily attached to the said bearing plates, said scraper being parallel with and yet independent of said contact rollers.

10. In a trolley, the combination with a frame provided with upper cheek pieces, bearing plates mounted to revolve upon the cheek pieces and means for holding the bearing plates in adjusted position, of a contact roller removably mounted in said bearing plates and a scraper removably fixed to the bearing plates, parallel with the roller, constituting a connecting medium, and a brace for the bearing plates when the said roller is removed.

11. In a trolley, the combination with a collapsible diamond-shaped frame consisting

of upper and lower pivotally connected members having their surfaces rounded at the junction of their parts, the upper ends of its upper members being upwardly curved and inwardly inclined, whereby the upper and lower members may be flatly folded upon each other, cheek pieces to which curved members the upper ends of the upper frame members are pivoted, bearing plates pivoted upon the cheek pieces, a locking device for the bearing plates, a contact roller journaled in the bearing plates and a scraper fixedly screwed to the said bearing plates.

12. In a trolley, the combination with a collapsible diamond-shaped frame consisting of upper and lower pivotally connected members having their surfaces rounded at the junction of their parts, the upper ends of its upper members being upwardly curved and inwardly inclined, whereby the upper and lower members may be flatly folded upon each other, cheek pieces to which curved members the upper ends of the upper frame members are pivoted, bearing plates pivoted upon the cheek pieces, a locking device for the bearing plates, a contact roller journaled in the bearing plates and a scraper fixedly screwed to the said bearing plates, protected meshing toothed segments at the upper ends of the upper members, protected meshing toothed segments at the lower ends of the lower members of the frame, a base upon which the said lower frame members are pivoted, and means for folding and unfolding the frames.

13. In a trolley, a collapsible frame, the inner ends of the opposing members whereof are enlarged, gears located at the inner faces of the said enlarged ends of the frame, being partially concealed thereby, cheek pieces with which the said enlarged ends of the frame members are connected, the gears of longitudinal opposing frame members being in mesh, and lips extending from said cheek pieces over the exposed portions of the gears and between the enlarged ends of the said frame members carrying the gears, whereby the gears are prevented from being jammed by forks or like members carried by the line wire.

In testimony whereof I have signed my name to this specification in the presence of two subscribing witnesses.

ALBERT S. JANIN.
